UNITED STATES PATENT OFFICE

141,286

DESIGN FOR A WHEEL TRIM OR SIMILAR ARTICLE

George Albert Lyon, Allenhurst, N. J.

Application July 29, 1944, Serial No. 114,615

Term of patent 14 years

(Cl. D14—30)

To all whom it may concern:

Be it known that I, George Albert Lyon, a citizen of the United States and a resident of the village of Allenhurst, in the county of Monmouth and State of New Jersey, have invented a new, original, and ornamental Design for a Wheel Trim or Similar Article, of which the following is a specification, reference being had to the accompanying drawing, forming a part thereof.

On the drawing:

Figure 1 is a side elevational view of my wheel trim, illustrating it applied to a tire and wheel, which are shown in dotted lines.

Figure 2 is a profile view showing the cross-sectional contour of my trim, and illustrating it

applied to a tire and wheel rim, which are shown in dotted lines.

Figure 3 is a profile view similar to a portion of Figure 2 but drawn on an enlarged scale.

In the drawing, the reference character A designates generally an annular trim portion and character B designates an outer ribbed bead. The dotted line showing of a wheel, rim and tire in Figures 1 and 2 being for illustrative purposes only.

I claim:

The ornamental design for a wheel trim or similar article, as shown and described.

GEORGE ALBERT LYON.
